UNITED STATES PATENT OFFICE

SAMUEL CLYDE KYLE, OF GREAT NECK, NEW YORK

DESIGN FOR A CABIN CRUISER

Application filed July 29, 1931. Serial No. 40,711. Term of patent 14 years.

To all whom it may concern:

Be it known that I, SAMUEL CLYDE KYLE, a citizen of the United States, residing in Great Neck, county of Queens and State of New York, have invented a new, original, and ornamental Design for Cabin Cruisers, of which the following is a specification, reference being had to the accompanying drawings, forming a part thereof.

Figure 1 is a side elevation of a cabin cruiser showing my new design,

Figure 2 is a plan view of the same, and

Figure 3 is a rear elevation of the same.

I claim:

The ornamental design for a cabin cruiser, substantially as shown.

SAMUEL CLYDE KYLE.
